UNITED STATES PATENT OFFICE

124,168

DESIGN FOR A DRESS ENSEMBLE

Marcia Backus, New York, N. Y.

Application September 26, 1940, Serial No. 95,388

Term of patent 3½ years

To all whom it may concern:

Be it known that I, Marcia Backus, a citizen of the United States, residing at 340 W. 37th Street, New York city, in the county of New York and State of New York, have invented a new, original, and ornamental Design for a Dress Ensemble, of which the following is a specification, reference being had to the accompanying drawing, forming part thereof.

The leaf-like elements down the front of the jacket at each side of the fasteners are quilted.

I claim:

The ornamental design for a dress ensemble, substantially as shown and described.

MARCIA BACKUS.
